UNITED STATES PATENT OFFICE.

RODOLPHUS FULLER, OF DETROIT, MICHIGAN.

DESIGN FOR AN ENGINE-FRAME.

SPECIFICATION forming part of Design No. 34,904, dated August 6, 1901.

Application filed May 31, 1901. Serial No. 62,675. Term of patent 14 years.

To all whom it may concern:

Be it known that I, RODOLPHUS FULLER, a citizen of the United States, residing at Detroit, in the county of Wayne and State of Michigan, have invented and produced a new and original Design for Engine-Frames, of which the following is a specification, reference being had to the accompanying drawings, forming a part hereof, in which—

Figure 1 is a perspective view of my design for an engine-frame. Fig. 2 is a front elevation, and Fig. 3 an end elevation, thereof.

As shown in the drawings, the leading or material feature of the design consists in giving to the frame the appearance of having a short elliptical neck portion uniting the crank-casing and upper portion.

As shown in the drawings, A is the cylinder and valve-casing, and B the crank-casing, both rectangular in form and united at their

adjacent ends by means of the elliptical neck portion C, giving to the engine-frame the appearance of having a body, a neck, and a head portion.

C' is an opening formed in the crank-casing adapted to receive a cover, and D the outwardly-flaring base portion, forming a downward continuation of the crank-casing.

Having thus fully described my invention, what I claim as new, and desire to secure by Letters Patent, is—

The design for an engine-frame, substantially as herein shown and described.

In testimony whereof I affix my signature in presence of two witnesses.

RODOLPHUS FULLER.
